FLOYD C. MERRITT

Frank L. Graham

ATTORNEY

UNITED STATES PATENT OFFICE

FLOYD C. MERRITT, OF LOS ANGELES, CALIFORNIA, ASSIGNOR TO ELLIOTT CORE DRILLING COMPANY, A CORPORATION OF CALIFORNIA

CORE DRILL CONSTRUCTION

Application filed September 6, 1927. Serial No. 217,689.

My invention relates to the art of making cores in oil wells, being more particularly a core drill of the double barrel type, in which a flushing fluid is utilized during the 5 drilling operation. Various types of core drills have been produced which are ordinarily satisfactory in most types of formation encountered, but in some instances, such as when what is known to the trade as a "cemented conglomerate" is encountered, which contains quartz, pebbles and other hard substances, the drills now commonly used have a tendency to spin during the drilling operation and in view of the fact that ordinarily 10 the flushing fluid is not carried sufficiently close to the cutting level, the teeth of such drills burn and fuse, thereby destroying the efficiency of the drill.

The principal object of my invention is to 20 produce a core drill of the class described, of simple form and construction in which a plurality of blades are used for the cutting operation and in which the flushing fluid is brought very close to the cutting level and in 25 close proximity to the forward face of the blades.

Other objects and advantages will appear hereinafter from the following description and drawings.

30 Referring to the drawings, which are for illustrative purposes only,

Fig. 1 is an elevation, partly in section, showing a drill embodying a form of my invention.

35 Fig. 2 is an elevation, partly in section, taken at a 90° angle to that shown in Fig. 1, and

Fig. 3 is a sectional plan view on line 3—3 of Fig. 2.

40 The drill consists of a cutter head 11 internally threaded at its upper end to receive a tool joint 12, the outer barrel of the drill indicated at 13 being threaded to the upper end of the tool joint. The head 11 consists of a hollow body having a fluid receiving recess 14. The lower end of the head is provided with dove tail slots 15 as shown in Fig. 3, converging inwardly to a central opening 16 formed in the head, such opening 16 terminating in a core receiving opening 17 at its

lower end, such core receiving opening being of smaller diameter than the opening 16, thereby forming a shoulder 18. Mounted in the slots 15 are four cutting blades 20 and 21, the cutting blades 20 being of substantially the same diameter as the head 11, and the cutting blades 21 extending outwardly therefrom to cut a hole of larger diameter than the head. These blades 20 and 21 are inserted in the head from the inside and, when 55 in place, are held in fixed relation to the head by means of a sleeve 25 seated on the shoulder 18, the upper end of the sleeve 25 being engaged by the lower end of an inner barrel 26, which is threaded into the opening 60 16 in the head.

It is to be understood that the sleeve 25 engages the inner face of the blades 20 and 21, thereby holding the same outwardly in the dove tail slots 15, the blades being similarly 70 shaped to fit such slots.

It is to be understood that the upper end of the inner barrel 26 is provided with a valve, not shown, as is ordinarily done in this class of drills, the upper end of the outer barrel 75 13 being connected to the drilling string, not shown.

Attention is called to the fact that the cutting edges 30 of the blades 20 extend below the lower end of the head 11, and the cutting 80 edges 31 of the blades 21 lie in a plane substantially above the plane of the edges 30, as shown in Fig. 2, such lower end of the head being rounded off as indicated at 32. The head is provided with fluid-discharge passages 33 connecting with the recess 14, which receives the fluid from an annular passage 34 formed between the inner and outer barrels. The fluid passages 33 terminate at their 85 lower ends in outlet openings 35 which are arranged adjacent to the forward face of the respective blades, as indicated in dotted lines at 36 in Fig. 3, such outlet openings 35 being also in the lower rounded end of the head, so that the fluid discharged is directly on the 90 forward face of the blades and adjacent to the cutting edge of the same, it being understood that the drill rotates in the direction of the arrow shown in Fig. 3.

If desired, a core catcher may be used, con- 100

sisting of a thimble 38 within the sleeve 25 and resting upon the shoulder 18, such core catcher being held in place by a split spring 39 of spring metal, arranged within the sleeve 5 25 above the core catcher 38. The core catcher 38 in the form shown is provided with a series of spring fingers 40, secured at their lower ends in any suitable manner to the core catcher and extending inwardly at their upper ends, as shown in Fig. 1.

I claim as my invention:

1. In a core drill, a cutter head having a core receiving opening with an inwardly extending shoulder and a fluid receiving recess 15 therein, a plurality of cutting blades mounted on said head having their cutting edges arranged at different cutting levels, means for holding said blades on said head comprising a removable sleeve resting on said shoulder, 20 and fluid discharge passages for said recess having discharge outlets located between said blades at different levels.

2. In a core drill, a cutter head having a plurality of dove tailed slots formed in the 25 lower end of said head extending therethrough, cutting blades in said slots extending outwardly from said head, said head having a central longitudinal opening terminating at its lower end in a reduced core receiving 30 opening forming a shoulder, and a removable sleeve resting on said shoulder engaging the inner face of said blades, said head having fluid discharge passages therein having discharge openings located between said blades.

3. In a core drill, a cutter head, an outer barrel attached to said cutter head, said head having a plurality of slots in its lower end extending therethrough, a cutting blade in each slot, a central longitudinal passage in 40 said head terminating at its lower end in a core receiving opening forming a shoulder in said passage, a sleeve seated on said shoulder engaging the inner faces of said blades, and an inner barrel mounted in said head in engagement with the upper end of said sleeve, 45 said head having a plurality of fluid discharge passages therein, having outlet openings located between the cutting blades.

4. For use in combination with a core drill, 50 a cutter head having a plurality of slots at its lower end extending through the wall of said head, a cutting blade in each slot, said head being provided with a central longitudinal passage therethrough having an inwardly extending shoulder at its lower end; a sleeve 55 downwardly seated on said shoulder engaging the inner faces of said blades, said sleeve being optionally removable through the upper end of said head; and a core catcher 60 mounted in said sleeve.

5. A cutter head for core drills comprising a hollow cylindrical body externally tapered inwardly at its lower outer end to form a rim about a core receiving opening said 85 body having plate-receiving slots, lower

blades removably mounted in some of said slots and extending outwardly from said body, said blades having cutting edges below said rim extending inwardly to the core receiving opening and upper blades removably mounted in others of said slots and extending outwardly through said body beyond said lower blades and having cutting edges above the cutting edges of said lower blades.

6. In a core drill; a cutter head having a fluid receiving recess therein; sets of cutter blades removably mounted in said head, one of said sets having cutting edges above the cutting edges of the other of said sets; and fluid discharge passages from said recess having sets of discharge outlets one above the other, said upper and lower sets of discharge outlets being arranged to flush the cutting edges of said upper and lower sets of blades respectively.

In testimony whereof, I have hereunto set my hand at Los Angeles, California, this 15 day of August, 1927.
